US0D1070914S

(12) **United States Design Patent** (10) Patent No.: **US D1,070,914 S**
(45) Date of Patent: ** Apr. 15, 2025

(54) **DISPLAY SCREEN OR PORTION THEREOF WITH AN ICON**

(71) Applicant: **DEERE & COMPANY**, Moline, IL (US)

(72) Inventors: **Nathanael K. Rehn**, Waterloo, IA (US); **Jeffrey M. Tott**, New Hartford, IA (US); **Trent L. Goodnight**, Hudson, IA (US)

(73) Assignee: **Deere & Company**, Moline, IL (US)

(**) Term: **15 Years**

(21) Appl. No.: **29/860,413**

(22) Filed: **Nov. 18, 2022**

Related U.S. Application Data

(63) Continuation of application No. 17/004,143, filed on Aug. 27, 2020, now Pat. No. 11,541,862.

(51) **LOC (15) Cl.** **14-04**

(52) **U.S. Cl.**

USPC **D14/492**

CPC **B60W 10/20** (2013.01); **B60W 40/105** (2013.01); **B60W 40/109** (2013.01); **B60W 50/10** (2013.01); **B62D 5/006** (2013.01); **B62D 5/091** (2013.01)

CLAIM

The ornamental design for a display screen or portion thereof with an icon, as shown and described.

DESCRIPTION

FIGURE is a front view of a display screen or portion thereof with an icon showing our new design.

The dot-dash broken lines illustrate a display screen and form no part of the claimed design.

1 Claim, 1 Drawing Sheet
